UNITED STATES PATENT OFFICE

134,162

DESIGN FOR A CUSPIDOR OR SIMILAR ARTICLE

Edward Grossman, Chicago, Ill.

Application June 3, 1942, Serial No. 107,086

Term of patent 3½ years

To all whom it may concern:

Be it known that I, Edward Grossman, a citizen of the United States and resident of Chicago, in the county of Cook and State of Illinois, have invented a new, original, and ornamental Design for a Cuspidor or Similar Article, of which the following is a specification, reference being had to the accompanying drawing, forming a part thereof.

Fig. 1 is a view in perspective of a cuspidor or similar article, showing my new design;

Fig. 2 is a side elevational view of the same on a reduced scale;

Fig. 3 is a rear elevational view of the same; and

Fig. 4 is an elevational view of the other side of same.

The features shown in broken lines are fanciful and do not represent any living individual.

I claim:

The ornamental design for a cuspidor or similar article, substantially as shown and described.

EDWARD GROSSMAN.
